UNITED STATES PATENT OFFICE.

DANIEL S. BAIRD, OF HAMILTON, ONTARIO, CANADA.

MAGAZINE-WRAPPING MACHINE.

Application filed January 24, 1924. Serial No. 638,319.

To all whom it may concern:

Be it known that I, DANIEL S. BAIRD, of the city of Hamilton, in the county of Wentworth, Province of Ontario, Canada, a subject of the King of Great Britain, have invented certain new and useful Improvements in Magazine-Wrapping Machines, of which the following is a specification.

This invention relates to magazine wrapping machines of the type employing rotatable forks which grasp the magazine near the forward edges of its ends, and roll it up with a sheet of paper having a gummed edge. In such machines it is necessary to withdraw the magazines one-by-one from a feeding trough, and to feed them forward in a substantially horizontal position over a feed table till their forward edges exactly reach a predetermined position, and my object 20 is to devise feeding means whereby the magazines are fed forward with certainty along the trough, are withdrawn and presented accurately to feed rollers and are fed by these rollers to a predetermined position on the table whatever the thickness of the magazine may be.

I attain my object by means of the constructions hereinafter fully described and illustrated in the accompanying drawings in 30 which—

Fig. 1 is a plan view of my improved feeding mechanism;

Fig. 2 a side elevation of the same;

Fig. 3 a side elevation of part of the 35 mechanism for lifting magazines to the feed roller;

Fig. 4 a similar view of another part of this mechanism;

Fig. 5 a detail, partly in elevation and 40 partly in section of the feed rollers;

Fig. 6 a perspective detail illustrating a portion of the magazine lifting mechanism; and

Fig. 7 a detail, partly in section, of one of 45 the feed wheels and its supporting and driving mechanism.

In the drawings like numerals of reference indicate corresponding parts in the different figures.

1 is the frame of the machine suitably shaped to support the different parts. On this frame is supported a table 2, over which the magazines are to be fed to the wrapping means such as hereinafter referred to.

55 Behind this table is supported a feeding

trough 3 which is open at the top, and is preferably inclined to facilitate the feeding of the magazines to the forward end. The front board 4 of the trough is preferably tangential to the periphery of the lower feed 60 roller 5 which is suitably journalled on the frame 1. With this roller co-operates the upper feed roller 6 which is mounted to rise and fall. In the preferred construction this roller is carried by the arms 7 which are 65 journalled on the shaft 8 journalled in the frame of the machine. This shaft is preferably positioned so that its axis is above the axis of the roller 6, when the latter is in engagement with the upper surface of a 70 comparatively thin magazine. The purpose of this will hereinafter appear.

The feed roller 6 is a driven roller, and to effect its driving I provide the following mechanism. The center of the roller is of 75 reduced diameter and a sprocket wheel 9 is secured thereto, which sprocket wheel is driven, by means of a sprocket chain, from the sprocket wheel 10 on the shaft 8. On the shaft 8 is also secured a sprocket wheel 80 11, driven by a suitable sprocket chain from the sprocket wheel 12 on the main shaft 13. A train of gearing 14 serves to drive the lower feed roller 5 from the shaft 8. The diameters of the two feed rollers are so proportioned that the periphery of the upper feed roll travels slightly faster than the periphery of the lower feed roller. The purpose of this is to overcome any tendency of the magazines to curl upwardly, instead of 90 lying flat, as they are pushed along the table 2.

I have sometimes found that magazines of different thickness require different ratios of speed between the surfaces of the two rollers. I therefore provide sleeves 15 of different external diameters which are adapted to be slipped over the ends of the roller and which form the magazine engaging parts thereof.

The magazine engaging parts of the roller 6 are provided with the alined notches 16 as indicated particularly in Fig. 5. The back of the magazine, when the latter is lifted, as hereinafter described, partly enters the notch or notches, one edge of which forms a sharp shoulder which engages the upper surface of the magazine and ensures a positive bite, so that the magazine starts on its forward movement the instance it is contacted 110

by the two rollers. I thus overcome the tendency to slip, which is the objection to the use of plain rollers, since it is imperative that each magazine is fed forward so that its 5 back, which is the leading edge, just reaches a predetermined position for engagement by the wrapping mechanism. I further found that if the upper feed roller were free to rise and fall, without limitation of its downward 10 movement, that a thick magazine will be fed forward further than a thin one, owing to the fact that the upper roller will remain in contact with it for a longer period than it would with a thin magazine. I therefore 15 provide means whereby the downward movement of the upper feed roller may be limited. For this purpose I provide the screws 17, threaded into the frame of the machine, and on which the reduced ends 18 20 of the feed roller 6 are adapted to rest. By adjusting these screws the time within which the upper feed roller is in contact with the magazine may be regulated. In producing the desired result, the specific arrangement 25 of the mounting of the upper feed roller assists, since its movement is rearwardly as well as downwardly, from which it results that its position when feeding a thick magazine is further to the rear than when feeding 30 a thin magazine, and a thick magazine therefore passes from engagement with it sooner than would otherwise be the case.

In case the weight of the upper feed roller is not sufficient for effective feeding I provide 35 a spring 19 which is secured to the frame and bears on the reduced center of the roller. The magazines are lifted for engagement with the feed rollers by the following mechanism. Disks 20 are slidably 40 and revolvably mounted on the reduced ends 21 of the lower feed roller 5, which disks carry sharply pointed fingers 22 adapted to enter between the leaves of a magazine, as indicated particularly in Fig. 6. Each finger 45 is preferably formed of one or more very thin pieces of steel set close together, so as to engage between the leaves of a magazine in different positions to ensure the magazine being lifted without being turned. 50 The lifting is effected by moving the disks toward the magazine to engage the fingers as shown in dotted lines in Fig. 6, then rotating the disks through an arc of about 90°, then sliding the disks outwardly to disengage 55 the fingers and finally rotating the disks in the reverse direction to return the fingers to their initial position. These movements are effected by the following mechanism. The shaft 23 is driven by a train of gearing 24 60 from the main shaft 13. This shaft carries two pairs of cams 25, 26. Each cam 25 is a face cam with high and low portions adapted to engage a shifter lever 27 fulcrumed 65 immediate its ends on the frame of the machine, and forked at its upper end to engage

a groove 28 formed in each disk 20. The other cam 26 of each pair is a rim cam provided with high and low portions adapted to engage a projection 29 on a slide rod 30, provided with a yoke 31, whereby it may 70 slide on the shaft 23. The upper end of this slide rod slides in a guide 32, secured to the frame of the machine, provided with a rack 33 engaging a pinion 34 secured to the corresponding disk 20. The pinions 34 are of sufficient length to permit them to be axially moved with their disks 20 and yet be engaged by the racks 33. The shaft is so driven and the cams so figured as to produce the sequence of movements of the disks 80 20 as hereinbefore referred to.

I have found that a simple inclined feed trough does not always feed forward the magazines to the front end of the trough with such certainty as to ensure them being 85 properly engaged by the lifting fingers and fed between the feed rollers. I therefore find it desirable to provide means whereby the magazines, no matter how many may be lying in the trough, will be properly fed forward and firmly pressed against the front 4 of the feed trough and the lower feed roller 5. For this purpose I provide an endless travelling band or tape 35 at the bottom 90 of the trough. This is mounted on rollers 36 in a manner common in the printing art. While the movement of the magazines is intermittent, this tape may be constantly driven as it slides readily by the magazines. To effect its driving, I therefore provide on 95 the forward roller 36 a sprocket wheel 37 driven by a suitable sprocket chain from the sprocket 38 on the main shaft 12. The magazines are placed in the trough with their backs uppermost, and it is therefore necessary that their backs should be firmly pressed against the front 4 of the feed trough and the lower feed roll. For this purpose I provide at each side a feed wheel 39. These wheels are resiliently pressed 100 against the magazine and are frictionally driven so that the drive slips at such times as the magazines are not able to move in the trough. The construction and arrangement 105 of these feeding wheels and their driving mechanism is best seen on reference to Figures 1, 2 and 7 of the drawings.

A bracket 40 is secured to the side of the feeding trough at each side of the machine. In this bracket is mounted a sliding bearing 41, through which passes a spindle 42 to which the feed wheel is secured. In the recess in the bracket is positioned a coil spring 43 which bears against the bearing 41. Threaded through the bracket is an adjusting screw 44, by means of which the tension 110 of the spring 43 may be adjusted. Slots 45 are provided in the bracket to provide the necessary play for the spindle 42. The spindle 42 is coupled, by means of a universal 115 120 125 130

joint 46, with a spindle 47 which passes through a yoke-shaped bracket 48. On this spindle 47 is secured a fixed collar 49. Journalled in the upper part of the bracket 58, and a loose collar 50. Between the jaws of the bracket a pulley 51 is positioned which is loose on the spindle 47. Suitable friction washers 52 are positioned between the pulley and the collars 49 and 50. On the lower end of the spindle 47 is positioned a coil spring 53 which bears against the loose collar 50 and against adjusting nuts 54 threaded on the end of the spindle. By means of these adjusting nuts the spring may be tensioned 5 to give the pulley 51 a frictional driving connection with the spindle. By suitable adjustment the driving effect of the feed wheels 39 on the magazines may be regulated as required.

20 The feed wheels 39 may be constructed in any suitable manner to grip the ends of the magazines, but I prefer to provide them with slight projections 55, which positively grip the leaves of the magazine. This arrangement gives satisfactory results.

To prevent the magazine next the front lifting with the front or leading magazine as the latter is lifted for engagement with the feed rollers, I provide the finger 56, secured 30 to the frame of the machine, and extending down behind the feed rollers to a position where it is engaged by the magazine as the latter is lifted by the fingers 22.

What I claim is:—

35 1. Magazine feeding mechanism comprising a feeding trough for the magazines in which they lie with their backs uppermost; a resiliently pressed feed wheel at one side of the feeding trough adapted to engage the ends of the magazines and mounted to move transversely relative to the feeding trough; means for rotating said wheel; and an endless travelling tape mounted at the bottom of the feeding trough and on which the magazines rest.

2. Magazine feeding mechanism comprising a feeding trough for the magazines in which they lie with their backs uppermost; an upwardly extending spindle journalled at 50 the side of the feeding trough adapted to swing to-and-from the trough; means for guiding said spindle; means for resiliently pressing it towards the trough; a feed wheel on said spindle adapted to engage the ends 55 of the magazines; and means for driving the spindle.

3. Magazine feeding mechanism comprising a feeding trough for the magazines in which they lie with their backs uppermost; 60 feed rollers at the forward end of the trough adjacent the backs of the magazines adapted to feed substantially horizontally, the front magazine contacting with the lower feed roller; means engaging the ends of the magazines adjacent their backs tending to press

them towards the lower feed roller; and means for lifting the magazines one-by-one to be gripped by the feed rollers.

4. Magazine feeding mechanism comprising a feeding trough for the magazines in 70 which they lie with their backs uppermost; feed rollers at the forward end of the trough adjacent the backs of the magazines adapted to feed substantially horizontally, the upper feed roller having a longitudinal notch 75 formed therein adapted to partly receive the back of a magazine; and means for lifting the magazines one-by-one to be gripped by the feed rollers.

5. Magazine feeding mechanism comprising a longitudinally inclined feeding trough for the magazines in which they lie with their backs uppermost; means engaging the lower edges and the ends of the magazines to facilitate their forward feed; feed rollers at the forward end of the trough adjacent the backs of the magazines adapted to feed substantially horizontally, the front magazine contacting with the lower feed roller; and means moving concentrically with the lower feed roller for lifting the magazines 85 one-by-one to be gripped by the feed rollers.

6. Magazine feeding mechanism comprising a feeding trough for the magazines; feed rollers at the top of the forward end of the trough adapted to feed substantially horizontally, the upper roller being vertically movable; adjustable means for limiting the movement of the upper roll towards the lower; and means for lifting the magazines 90 one-by-one to be gripped by the feed rollers.

7. Magazine feeding mechanism comprising a feeding trough for the magazines; feed rollers at the top of the forward end of the trough adapted to feed substantially horizontally, the upper roller being vertically movable in a direction inclined rearwardly and upwardly relative to the direction of feed of the magazines; adjustable means for limiting the movement of the upper roll towards the lower; and means for lifting the magazines one-by-one to be gripped by the feed rollers.

8. Magazine feeding mechanism comprising a feeding trough for the magazines in which they lie with their backs uppermost; feed rollers at the forward end of the trough adjacent the backs of the magazines adapted to feed substantially horizontally; and means for lifting the magazines one-by-one to be gripped by the feed rollers comprising fingers adapted to enter between the leaves of a magazine at each end, and means for alternately extending and retracting said fingers and for oscillating them in an arc of a circle substantially concentric with the lower feed roller.

9. Magazine feeding mechanism comprising a feeding trough for the magazines in which they lie with their backs uppermost;

feed rollers at the forward end of the trough adjacent the backs of the magazines adapted to feed substantially horizontally; and means for lifting the magazines one-by-one to be gripped by the feed rollers comprising disks journaled concentric with the lower feed roller, fingers on said disks adapted to enter between the leaves of a magazine at each end, means for oscillating said disks, and means for moving them axially to extend and retract said fingers.

10. Magazine feeding mechanism comprising a feeding trough for the magazines in which they lie with their backs uppermost; a resiliently pressed feed wheel at one side of the feeding trough adapted to engage the ends of the magazines and mounted to move transversely relative to the feeding trough; and a frictional drive for said wheel.

15. Magazine feeding mechanism comprising a feeding trough for the magazines in which they lie with their backs uppermost; an upwardly extending spindle journaled at the side of the feeding trough adapted to swing to-and-from the trough; means for guiding said spindle; means for resiliently pressing it towards the trough; a feed wheel on said spindle adapted to engage the ends of the magazines; and a frictional drive for said wheel.

20. Magazine feeding mechanism comprising a feeding trough for the magazines in which they lie with their backs uppermost; a resiliently pressed feed wheel at one side of the feeding trough adapted to engage the ends of the magazine and mounted to move transversely relative to the feeding trough; and means for rotating said wheel including a friction drive.

25. Magazine feeding mechanism comprising a feeding trough for the magazines in which they lie with their backs uppermost; an upwardly extending spindle journaled at the side of the feeding trough adapted to swing to-and-from the trough; means for guiding said spindle; means for resiliently pressing it towards the trough; a feed wheel on said spindle adapted to engage the ends of the magazines; and means for driving the spindle including a friction drive.

30. Magazine feeding mechanism comprising a feeding trough for the magazines in which they lie with their backs uppermost; an upwardly extending spindle journaled at the side of the feeding trough adapted to swing to-and-from the trough; means for guiding said spindle; means for resiliently pressing it towards the trough; a feed wheel on said spindle adapted to engage the ends of the magazines; means for driving the spindle including a friction drive; and an endless travelling tape mounted at the bottom of the feeding trough and on which the magazines rest.

35. Magazine feeding mechanism comprising

ing a feeding trough for the magazines in which they lie with their backs uppermost; feed rollers at the forward end of the trough adjacent the backs of the magazines adapted to feed the magazines substantially horizontally, the upper feed roller having a removable sleeve forming its driving surface; and means for lifting the magazines one-by-one to be gripped by the feed rollers.

16. Magazine feeding mechanism comprising a feeding trough for the magazines in which they lie with their backs uppermost; feed rollers at the forward end of the trough adjacent the backs of the magazines adapted to feed the magazines substantially horizontally, the upper feed roller having a removable sleeve forming its driving surface and provided with a notch adapted to partly receive the back of a magazine; and means for lifting the magazines one-by-one to be gripped by the feed rollers.

17. Magazine feeding mechanism comprising a trough for the magazines in which they lie on edge; resiliently pressed feeding means at the side of the trough adapted to engage the ends of the magazines and mounted to move transversely relative to the said feeding trough; and a frictional drive for said means.

18. Magazine feeding mechanism comprising a trough for the magazines in which they lie on edge; resiliently pressed feeding means at the side of the trough adapted to engage the ends of the magazines and mounted to move transversely relative to the said feeding trough; a frictional drive for said means; and an endless travelling tape mounted at the bottom of the feeding trough and on which the magazines rest.

19. Magazine feeding mechanism comprising a feeding trough for the magazines in which they lie with their backs uppermost; feed rollers at the forward end of the trough adjacent the backs of the magazines adapted to feed the magazines substantially horizontally, means for rotating said feed rollers at the same spindle speed, the upper feed roller being of greater diameter than the lower feed roller whereby its peripheral speed is greater.

20. Magazine feeding mechanism comprising a trough for the magazines in which they lie on edge; resiliently pressed feeding means at the side of the trough adapted to engage the ends of the magazines and mounted to move transversely relative to the said feeding trough; a frictional drive for said means; and means frictionally engaging the bottom edges of the magazines and tending to move them forward in the trough.

21. Magazine feeding mechanism comprising a feeding trough for the magazines in which they lie with their backs uppermost; a resiliently pressed feed wheel at one side of the feeding trough adapted to engage the

ends of the magazines and mounted to move transversely relative to the feeding trough; means for rotating said wheel; and means frictionally engaging the bottom edges of the magazines and tending to move them forward in the trough.

22. Magazine feeding mechanism comprising a trough for the magazines; a pair of

feed rollers one above the other; means engaging the edges of the magazines adapted to press them towards the lower feed roller with the front magazine in contact therewith; and means for lifting the front magazine to be gripped between the rollers.

DANIEL S. BAIRD.
